UNITED STATES PATENT OFFICE.

ALEXANDER CLARKE AND JOHN F. CLARKE, OF ESSEX CENTRE, ONTARIO,
CANADA.

COMBINATION-TOOL.

SPECIFICATION forming part of Letters Patent No. 423,513, dated March 18, 1890.

Application filed April 29, 1889. Serial No. 309,108. (No model.)

To all whom it may concern:

Be it known that we, ALEXANDER CLARKE and JOHN F. CLARKE, subjects of the Queen of Great Britain, residing at Essex Centre, county of Essex, Province of Ontario, Canada, have invented certain new and useful Improvements in a Combination-Tool; and we declare the following to be a full, clear, and exact description of the invention, such as will enable others skilled in the art to which it appertains to make and use the same, reference being had to the accompanying drawings, which form a part of this specification.

Our invention has for its object to provide a novel combination-tool, to be used in any ordinary bit-stock, the combined tool having a variety of useful tools, such as are more ordinarily in demand, in connection therewith, while, also, any other desired tool of the same general class can be readily engaged therewith, as may be required.

We carry out our invention as more fully hereinafter described, and set forth in the claims, and more fully illustrated in the accompanying drawings, in which—

Figure 1 is a view in perspective of a device embodying our invention. Fig. 2 is a vertical section through the jaws, showing one of the jaws in elevation, with catch in position. Fig. 3 is a similar section showing the other jaw and certain of the various tools in engagement therewith, with catch removed. Fig. 4 is a top plan. Fig. 5 is a separate view of the spring, and Fig. 6 shows a detail view of the shank of a separable tool to be engaged in the jaws of the combined tool.

For many purposes—as, for instance, in carriage-making, for domestic uses, for farmers, and the like—where a kit of tools is not desired or where tools are needed in most convenient form, a combination-tool of the description herein set forth and illustrated will be found to facilitate labor, economize time, and embody in itself a cheap device capable of a great variety of services.

We carry out our invention as follows:

A and A' represent jaws constituting the body of our improved tool. As shown, said body may consist of two jaws properly united in any desired manner. In the drawings they are shown connected by a rivet x . These jaws

may be cast, and may be, preferably, tapering toward the base, where they are engaged by a ferrule B, preferably milled on its exterior. Sleeved through said ferrule is a shank 55 C, constructed at one extremity to be engaged in any ordinary bit-stock. At the opposite end the shank has a screw-threaded engagement with the jaws.

We do not limit ourselves exclusively to the definite construction of jaws illustrated herewith, nor to any definite manner of engaging the shank C therewith. When the shank is engaged in a bit-stock, one hand may grasp the ferrule B to steady the tool and 65 keep it in place. The jaws are recessed at their upper ends, as shown at a a' a^2 a^3 , to receive a series of tools, which may be pivotally engaged or otherwise jointedly united with the jaws. Thus, for example, D is a 70 screw-driver; D', a gimlet; D² and D³, different styles of reamers.

We do not limit ourselves to any specific kind of tools to be united with the jaws nor to any particular number of them. We have 75 shown four in the accompanying drawings, but more or less might be employed without departing from our invention.

To effect the proper jointed union of the tools D D' D² D³ with the jaws, their tangs 80 are constructed with an inwardly-extended shoulder d , through which pivots d' unite the individual tools with the jaws. As so constructed, when not in use the individual tools may be turned down alongside the jaws, as 85 shown, out of the way, in which position they may be held securely in any desired manner—as, for instance, by a friction-post d^2 —or the frictional contact of the shoulders d of the tools in the recesses a a' a^2 a^3 , respectively, 90 may serve to hold the tools in place alongside the jaws. Any desired means for so holding the tools in place when not in use may be employed. To effect the entrance of the pivots d' , the jaws may be hollowed out 95 adjacent thereto, as shown at a^4 . We do not limit ourselves to the pivots for uniting the individual tools in the jaws.

Where it is desirable to facilitate the removal of a given tool from the jaws, a spring-100 stud d^3 might be employed. As shown, the end of the stud is secured to a short flat

spring, the latter held normally in close proximity to the surface of the jaw by a rivet or bolt, which secures it thereto, the end to which the stud is attached having a yielding movement away from the surface to release the stud from the tool. As so hung or engaged in the jaws it is evident that any given tool of the series may be erected in position for use, as shown, for example, in Fig. 1. Being provided with the shoulder d , through which the tools are pivoted to the jaws at one side of the center of the united jaws, it is evident that the tools when erected for use will be thrown to the center of the jaws.

15 To hold the tools in an erect position, we provide a spring-latch E , having a jointed or other proper union with the jaws, constructed to engage the shoulders of the tools and hold them in a firm position. Thus the latch may 20 be constructed with a notched head e and an arm e' , extended through one of the jaws, within easy reach of the thumb or finger of the operator, by pressing upon which the tool may be released and turned out of the way, 25 a spring e^2 restoring the latch to its normal position. The individual tools may be constructed with shoulders d , notched as at d^4 , to engage the latch, a single latch serving to hold all the tools successively in an erect position.

30 Should it be desired to use a separable tool with the jaws, as a tool F , Fig. 6, for any purpose, its shank may be formed to enter the open end of the jaws, as shown in Fig. 4, for instance, and engage the spring-latch E .

35 What we claim is—

1. A combination-tool having a body portion provided with a central opening in one end, and with radial slots or openings extend-

ing from the central opening through to the outside of the tool, tools hinged in the radial 40 slots, and a central catch adapted to automatically engage any one of the tools when swung into extended position for use, substantially as set forth.

2. A combination-tool having a body portion provided with openings in its end, tools hinged in the openings, a ferrule loosely secured on the shank end of the body portion for holding the tool, and a catch adapted to engage the tools and lock them in working 50 adjustment, substantially as set forth.

3. A combination-tool having a body portion provided with a central opening in one end, and with slots or openings extending radially from the central opening through to the outside of the body, tools hinged in the said slots, the hinged ends of the tools forming, when the tools are folded, the walls of an opening to receive a separable tool, and a catch for engaging the tools, substantially as 60 set forth.

4. A combination-tool comprising a body portion formed of united jaws or sections, and provided with a central opening and slots radiating from one end thereof, a shank engaged with the body, and a series of tools having a jointed engagement with said body, substantially as set forth.

In testimony whereof we sign this specification in the presence of two witnesses.

ALEXANDER CLARKE.
JOHN F. CLARKE.
